UNITED STATES PATENT OFFICE

141,545

DESIGN FOR A WRENCH

Earle Fleming, Los Angeles, Calif.

Application November 20, 1944, Serial No. 116,456

Term of patent 14 years

(Cl. D54—16)

To all whom it may concern:

Be it known that I, Earle Fleming, a citizen of the United States, residing at Los Angeles, in the county of Los Angeles and State of California, have invented a new, original, and ornamental Design for Wrench, of which the following is a specification, reference being had to the accompanying drawing, forming part thereof.

Figure 1 is a side view of a wrench, showing my new design; Figure 2 is an end view of the wrench, looking in the direction of the arrow 2;

and Figure 3 is an opposite end view of the wrench, looking in the direction of the arrow 3.

The dominant features of my design are the specific shapes and configurations of the jaws composing the head of the wrench, in their relationship as shown.

I claim:

The ornamental design for a wrench, as shown and described.

EARLE FLEMING.
